UNITED STATES PATENT OFFICE.

JOHN HOLTZMANN, OF BALTIMORE, MARYLAND.

SEWING-MACHINE HEMMER.

1,073,757.

Specification of Letters Patent. Patented Sept. 23, 1913.

Application filed May 10, 1913. Serial No. 766,802.

To all whom it may concern:

Be it known that I, JOHN HOLTZMANN, a citizen of the United States, residing at Baltimore, in the State of Maryland, have 5 invented or discovered certain new and useful Improvements in Sewing-Machine Hemmers, of which the following is a specification, reference being had therein to the accompanying drawing.

10 This invention relates to sewing machine hemmers, and has for its object to provide an adjustable hemmer adapted to form hems of varying widths, and which is of such construction that adjustments for varying the 15 widths of the hems may be effected while the machine is running. In doing certain classes of work it is necessary or desirable, as in making open front shirts, to vary the width of a hem in forming a single 20 continuous seam. As this work has heretofore been performed it has been customary to make one portion of the hem on one machine and the other portion of the hem on another machine fitted with a hemmer of a 25 different width, this being more convenient than it would be to adjust the hemmer to a different width, or to change the hemmer for one of a different width and thus make the 30 hems of different widths on the same machine. Such a procedure would require a double handling of the work, in either instance. This objection as to a double handling of the work is avoided by the present 35 invention which provides a hemmer which may be adjusted, to vary the width of the hem, while the machine is running, so that the character of the hem may be instantly changed, without stopping the machine, from a wide to a narrow hem, or vice versa. 40 The improved hemmer by which this invention may be carried into effect comprises two cloth-turning and guiding members the distance apart of which may be varied to form hems of different widths. In the preferred embodiment of the invention the scroll 45 portion of the hemmer, by which the edge of the cloth is turned under the fold, is fixed, while the opposite cloth-turning and guiding portion of the hemmer is mounted on one arm of a pivoted member or lever the 50 other arm of said pivoted member or lever, and which is preferably a spring arm, being provided with means by which it may be grasped by the thumb and finger of the attendant for the purpose of adjustment, while the base plate of the hemmer is provided

with a catch into which the said spring arm will snap when the pivoted member or lever is adjusted for forming narrow hems, all as will hereinafter more fully appear. 60

In the accompanying drawings Figure 1 is a plan view showing one form of the invention, and Fig. 2 is a front edge view of the same. Fig. 3 is a plan view of a slightly different form of the invention 65 from that shown in Fig. 1, and Fig. 4 is a front edge view of the form of the invention shown in Fig. 3.

Referring to the drawing, 12 denotes a base-plate which is preferably provided with 70 a slot 13 for the reception of a set-screw by which said base-plate may be attached to the work-plate of a sewing machine, said base-plate being provided at its end farthest removed from said slot with a lug 14 adapted 75 to engage a slot or recess in the work-plate of a sewing machine. Fixedly mounted on the base plate 12, preferably by being soldered thereto, is a complete scroll hemmer 15 which is of well-known form, and which 80 comprises a depending cloth-turning and guiding scroll portion 16 which turns under the edge of the cloth in forming a hem.

Pivotedly mounted on the base-plate 12, by means of a pin 17, is a member or lever 85 comprising two arms 18 and 19. The arm 18 is provided with a cloth-turning and guiding scroll or transversely curved portion 20 which is shaped to correspond to that wall or upturned curved scroll portion 90 21 of the hemmer 15 opposite to the scroll portion 16 thereof, so that the said scroll portion 20 serves the purpose ordinarily performed by the side wall or portion 21 of the hemmer in turning and guiding the 95 cloth at a hemming operation. The arm 19 is formed of spring metal, and, in the form of the invention shown in Figs. 1 and 2, is provided with an upstanding part or projection 22 adapted to be grasped by the 100 thumb and finger of the attendant when the two-armed pivoted member or lever is to be adjusted to vary the distance between the fixed cloth-turning and guiding member 16 and the adjustable cloth-turning and guiding member 20 which is mounted on the arm 18 of the pivoted member or lever, in forming hems of different widths. 105

The base plate is provided with a catch 110 consisting of a small plate 23 secured thereto and provided with a notch 24 adapted to receive a portion of the arm 19 of the pivot-

ed member or lever, said arm springing into and being retained in said notch by its own resilience when brought into register therewith and being adapted to be lifted from 5 said notch when an adjustment is to be made for the purpose of varying the width of the hemmer.

When, in the use of the form of the invention shown in Figs. 1 and 2, the pivoted 10 member or lever 18-19 is adjusted to form a wide hem the cloth-turning and guiding member 20 will be in contact with the portion 21 of the hemmer 15, so that the said portion 21 serves as a stop to limit the further movement of the said member 20 of 15 the hemmer; while the cloth passing through the hemmer will press against the inside of said member 20 and thus tend to hold it against the portion 21 of the hemmer 15. In other words, the passing roll or 20 scroll of cloth to form the hem, being confined between the depending left hand fixed scroll portion 16 and the upturned adjustable scroll portion 20, will exert a constant pressure to the right on said scroll portion 25 20, to maintain it against the portion 21, in the form of the invention shown in Figs. 1 and 2, or to maintain the stop-screw 25 against the lug 26 in the form of the invention shown in Figs. 3 and 4. When, 30 however, the adjustment of the hemmer is to be changed from wide to narrow hemming a slight pressure of the thumb or finger of the attendant against the front side of the upstanding part or projection 22 will bring the arm 19 into register with the notch 22 so that the said arm will instantly spring into said notch when the said arm has been moved the proper distance to narrow the 35 hem to a desired width, causing the cloth-turning and guiding member 20 to approach the cloth-turning and guiding member 16 in performing such adjustment.

The adjustment and operation of the form 45 of the invention shown in Figs. 3 and 4 is just the same as that described with reference to the form of the invention shown in Figs. 1 and 2, excepting that in the construction shown in Figs. 3 and 4 the arm 19 is provided with an adjustable stop screw 50 25 adapted to abut against a lug 26 on the plate 23 provided with the catch notch 24, this construction providing for making wide hemms of somewhat different widths, depending 55 upon the position of adjustment of the said stop screw 25 which is tapped in the portion 27 of the said arm 19. For convenience of adjustment, in this form of the invention, the arm 19 is preferably provided 60 with a knob 28 which may be grasped by the thumb and finger of the attendant in lifting said arm out of its catch notch 24.

From the foregoing it will be understood 65 that when the improved hemmer is attached to a sewing machine in operative re-

lation to the stitch-forming mechanism thereof, with the hemmer in front of the needle of the machine, an adjustment of the hemmer, to vary the distance between the fixed cloth-turning and guiding member 16 70 and the adjustable cloth-turning and guiding member 20 may be instantly effected, while the machine is running, for the purpose of changing from a wide to a narrow hem, or vice versa, thus enabling a continuous hem of varying widths to be made at a continuous or uninterrupted operation, and thereby facilitating and expediting that class of work in which it is desirable to vary the width of a continuous hem at certain 80 parts thereof.

The invention is not to be understood as being limited to the details of construction herein shown and described, as such details may be varied without departing from the 85 scope of the invention as defined by the claims hereunto appended.

Having thus described my invention I claim and desire to secure by Letters Patent:

1. An adjustable sewing machine hemmer 90 comprising a complete fixed scroll hemmer having depending and upturned portions, and an upturned scroll member arranged between the upturned and depending portions of said complete hemmer and adjustably 95 mounted so that the distance between said fixed depending portion and said last-named upturned scroll member may be varied, combined with a two-armed lever on one arm of which said adjustable upturned scroll member is mounted.

2. An adjustable sewing machine hemmer 105 comprising a complete fixed scroll hemmer having depending and upturned portions, and an upturned scroll member arranged between the upturned and depending portions of said complete hemmer and adjustably mounted so that the distance between said fixed depending portion and said last-named upturned scroll member may be 110 varied, combined with a two-armed lever on one arm of which said adjustable upturned scroll member is mounted, and means for holding said lever in different positions of adjustment.

3. An adjustable sewing machine hemmer 115 comprising a complete fixed scroll hemmer having depending and upturned portions, and an upturned scroll member arranged 120 between the upturned and depending portions of said complete hemmer and adjustably mounted so that the distance between said fixed depending portion and said last-named upturned scroll member may be varied, combined with a two-armed lever on one arm of which said adjustable upturned scroll member is mounted, and a catch with 125 which the other arm of said lever may be engaged when the hemmer is adjusted for narrow hemms.

4. An adjustable sewing machine hemmer comprising a complete fixed scroll hemmer having depending and upturned portions, and an upturned scroll member arranged between the upturned and depending portions of said complete hemmer and adjustably mounted so that the distance between said fixed depending portion and said last-named upturned scroll member may be varied, combined with a two-armed lever on one arm of which said adjustable upturned scroll member is mounted, means for hold-

ing said lever in different positions of adjustment, and adjustable means on the other arm of said lever whereby the working position of said adjustable upturned scroll member may be varied when the hemmer is adjusted for wider hems. 15

In testimony whereof I affix my signature, in presence of two witnesses.

JOHN HOLTZMANN.
